S. Kingsland,
Bending Wood,
No 35,983, Patented July 22, 1862.

Inventor

Samuel Kingsland

UNITED STATES PATENT OFFICE.

SAMUEL KINGSLAND, OF LYNDON, WISCONSIN.

IMPROVED WOOD-BENDING MACHINE.

Specification forming part of Letters Patent No. 35,983, dated July 22, 1862.

To all whom it may concern:

Be it known that I, SAMUEL KINGSLAND, of the town of Lyndon, county of Juneau, and State of Wisconsin, have invented a new and useful Machine for Bending Wood; and I do hereby declare that the following is a full and exact description thereof, reference being had to the accompanying drawings, and to the letters of reference marked thereon, in which—

Figure 1 is a top or plan view, and Fig. 2 a side view, of the same.

The nature of my invention consists in providing suitable mechanism, in connection with a heated cylinder, whereby the wood in an unseasoned state, or, if seasoned, after having been soaked in water, is bent in any desired form over said heated cylinder and retained in that position until, by a process of seasoning or evaporation, it is caused to permanently retain the form imparted to it by the bending process herein described.

To enable others skilled in the art to make and use my invention, I will proceed to describe its construction and operation.

I construct a hollow cylinder, of cast-iron or other suitable material, of any desired form and size, or parts of which may be of different sizes and form, as represented in the drawings, where B is a continuation of the cylinder A of less dimension, and consequently of less curvature. This may be again subdivided in its extent, laterally, so as to present in the same machine a series of forms, being parts or sections of the same hollow cylinder. An opening is provided in said cylinder at some suitable point, as at h, for the introduction of fuel, the same being provided with suitable means for securely closing the same, so as to prevent the escape of the fuel when the cylinder is revolved, or to prevent the escape of ashes or smoke, which would otherwise interfere with the operation thereof. At one end of this cylinder is provided, by suitable means for revolving it, a crank, e, with its handle f, through the axis of which is an aperture, b, for the purpose of furnishing ventilation to the fire-chamber within said cylinder, which passes its entire length, and is provided at the other end with a suitable pipe or chimney to secure the necessary draft, and to convey away through the roof of the building or into the chimney the smoke or gases from within the cylinder. The lower extremity of this chim-

ney or pipe is fitted over a projection of the cylinder, which revolves with it, so that the same may revolve within the pipe, and through which the smoke passes into it, as represented at O in Fig. 1. At suitable points on the exterior of the said cylinder is provided appropriate gearing, d', as represented in Fig. 2 and at d', Fig. 1. At each end, and at suitable intermediate points on said cylinder, are provided suitable journals, to be supported and revolve on the bearings in plates C C' C'', as hereinafter more particularly described. The plates C C' C'', or any desired series of them, serve as the frame upon which the cylinder and other mechanism of my invention are supported. The outer plate, C, as represented in the drawings, which supports the end of the cylinder into which the fuel is fed, as represented, is provided with a sufficient opening or bearing for the journal on which the crank e is fixed; and said plate is so formed on its upper and inner edge as to correspond with the form of the cylinder, and extending above the cylinder, as represented in Fig. 2, for the purpose of mounting above it a series of feed-rollers, with their gearing, set-screws, and bearings, as shown. Upon the curved edge of said plate C is secured, by screws s, a plate, j, with its corrugated or projecting edges n. Corresponding to said projecting edges n of said plate j, and immediately under them, are projections v, fastened securely to or cast with the said plate C. Immediately under the projections v are cut, in said plate C, the beveled slots t, into which are fitted the sliding boxes m, provided at their upper ends with projections v'. The slots t are cut with beveled edges inwardly, and the sliding boxes m have their corresponding beveled edges so that the said boxes cannot pass through said slot outwardly, but are perfectly free to move up and down therein and are removable inwardly. Through the projections n, v, and v' are passed the set-screws g g g, for the purpose of adjusting the sliding boxes m up and down in the slots t, as may be desired. Near the center of the sliding boxes m are suitable holes or bearings to receive the journals of the feed-rollers a a a a, as shown in Fig. 2. The feed-rollers a a a a are provided with pinions which mesh into and are operated by the gearing d' on the cylinder. A corresponding plate, C', provided with a plate, j, with its projections n, beveled

slots t , sliding boxes m , with their bearings to receive the other end of the feed-rollers a , projections v and v' , and set-screws g for the support and adjustment of said feed-rollers at the other end, is provided, as represented in Fig. 1. A plate, C' , is shown in the drawings as a support for the other end of the cylinder, and is provided with a suitable bearing for the support of its journal, and through which passes the projection to receive the pipe c' , and to the upper edge of which is secured a support, n' , through which in its upward angle passes said pipe. The plates $C C' C''$ are secured firmly in the desired position by cross-braces $a' a'$, suitably bolted, and a cross-tie of timber, m' , at their outer end. The cross-braces a' also serve as a fulcrum to receive the end of the wood to be bent over the part of the cylinder B by hand manipulation or other suitable means.

The operation of the machine, with reference to the feed-rollers, is: After sufficiently heating the cylinder A the wood to be bent is inserted in an unseasoned or soaked state between the feed-rollers a and the heated cylinder, the said rollers having been properly adjusted by means of said set-screws. Then, by revolving the crank, the wood is drawn in between the heated cylinder and feed-rollers and around the cylinder, and is thus retained until sufficiently seasoned to retain its new form, the same being for a few minutes only. The crank is then turned back so as to discharge the bent wood, preparatory to a repetition of the operation; or, for light work, the bending process may be conducted by hand manipulation, as stated, the bent wood being retained in place by any suitable fastening the desired time for the drying or seasoning process.

The peculiar advantage of my invention consists in the use of a heated cylinder having its external walls of suitable form for bending wood as may be desired, in connection with

the means for operating the same, as described, whereby the steaming process preparatory to wood-bending is avoided and a most permanent result secured, of any desired form, of a lasting nature, in a very few moments of time, the wood passing into the machine in an unseasoned or soaked state and being delivered therefrom, without material delay, permanently bent and in a dry and seasoned condition, supplying an article which will be proof against weather and will retain its new form under every condition and use.

Having thus described my invention, what I desire to secure by Letters Patent is—

1. The application to wood-bending of hollow cylindrical forms, constructed, arranged, and operated as herein described.

2. The construction and arrangement of the metal plates $C C' C''$, in combination with the hollow cylinder $A B$, arranged thereon and secured together by the cross-braces $a' a'$ and cross-tie m' , with their journals and journal-bearings, crank e , door h , draft-hole b , and pipe c , all arranged in the manner and for the purpose specified.

3. The peculiar means of adjustment for the feed-rollers $a a' a$ by means of the projections n , v , and v' , set-screws g , and sliding boxes m , all being arranged, constructed, and operating in the manner and for the purpose described.

4. A wood-bending machine combining a heated cylinder or cylindrical forms supported by plates $C C' C''$, or equivalent means, with their means of adjustment as described, supplied with fuel and heated in the manner described, and operated by a crank or other equivalent means, substantially as and for the purpose specified.

SAML. KINGSLAND.
